UNITED STATES PATENT OFFICE.

THEODORE E. STRAUS, OF BALTIMORE, MARYLAND, ASSIGNOR TO WORTHINGTON
COTTON HARVESTER COMPANY, OF BALTIMORE, MARYLAND, A CORPORATION
OF DELAWARE.

PNEUMATIC COTTON-PICKER.

1,188,700.

Specification of Letters Patent. Patented June 27, 1916.

Application filed April 17, 1914. Serial No. 832,589.

To all whom it may concern:

Be it known that I, THEODORE E. STRAUS, a citizen of the United States, residing at Baltimore, State of Maryland, have invented 5 certain new and useful Improvements in Pneumatic Cotton-Pickers, of which the following is a description, reference being had to the accompanying drawing and to the figures of reference marked thereon.

10 The invention relates to new and useful improvements in pneumatic cotton pickers, and more particularly to cotton pickers wherein the nozzle is provided with rotating means to assist in disengaging the cotton 15 fiber from the boll.

An object of the invention is to provide a pneumatic cotton picking nozzle, which is formed with an inner and an outer section adapted to be rotated relative to each other, 20 whereby the cotton fiber is engaged and held from outward movement by the inner section and twisted from the cotton boll which is held from movement relative to the cotton fiber by the outer section.

25 A further object of the invention is to provide a cotton picker of the above type, with devices which not only hold the boll from rotating relative to the cotton fiber as it is stripped therefrom, but which also positively moves the boll outward away from the cotton fiber and away from the maximum 30 point of suction, so as to facilitate the releasing of the boll from the cotton and to prevent the boll from being drawn into the 35 suction nozzle.

A still further object of the invention is to provide a cotton picking nozzle of the above type, wherein the inner and outer sections are so constructed and arranged relative to 40 each other as to permit air to enter the nozzle between the sections, so that the amount of air passing through the outer section and forcing the cotton fiber into the inner nozzle is slightly less than the amount of air which 45 finally conveys the cotton through the inner nozzle section.

These and other objects will in part be obvious and will in part be hereinafter more fully disclosed.

50 In the drawings—Figure 1 is a longitudinal sectional view, showing a picking nozzle having my improvement applied thereto; Fig. 2 is an end view of the same; Fig. 3 is a perspective view of the outer section of the 55 nozzle; Fig. 4 is a view similar to Fig. 1,

showing a modified form of the invention, wherein the outer section rotates; and Fig. 5 is a view similar to Fig. 4, showing a still further modified form of the invention, wherein both the inner and outer sections are 60 rotated in opposite directions.

The invention consists generally in providing a picking nozzle which is formed with a tubular shank connected by suitable means to a source of suction. At the outer 65 end of this tubular shank is a supporting frame on which is mounted the inner section of the nozzle. This inner section of the nozzle is preferably bell-shaped and is provided with means for engaging the cotton fiber 70 and holding the same from outward movement relative thereto. Also mounted on the supporting frame is the outer section of the nozzle. This outer section of the nozzle is 75 preferably in the shape of an annulus, which is concavo-convex in cross section. This outer section is located adjacent the extreme outer edge of the bell of the inner section and is so disposed relative thereto as to receive the edge of the bell. It is, however, 80 spaced from said bell so as to permit the air to pass underneath the same. The inner and outer sections are rotated relative to each other. Either the inner section may be made to rotate or the outer section or 85 both, and when both are rotated said sections rotate in opposite directions. The outer section is provided with outwardly projecting members or wings which extend inwardly toward the center of the nozzle to 90 restrict somewhat the passage through the outer section. These members or wings are also inclined so that when the boll is rotated relative to this outer section or the outer section is rotated relative to the boll, said boll 95 will be forced upward by these projections or members to aid in stripping the cotton fiber therefrom.

Referring more in detail to the drawings, 100 my improved cotton picking nozzle consists of a supporting shank 1, which is connected by the usual flexible pipe to a source of suction. This shank 1 carries a picking nozzle, which, as shown in Fig. 1, consists of a supporting frame 2, threaded on to said shank 105 and locked thereon by a collar 3. This supporting frame is in the form of a housing. The picking nozzle is formed with two sections, an inner section 4 and an outer section 5. This inner section 4 is threaded on 110

to a rotating support 6. The rotating support 6 has an inner sleeve 7, which is in line with the shank 1 and placed end to end with the shank. A disk 8 extends outwardly 5 from this sleeve and it is formed with a flange 9, which at its inner end has a bearing 10 on the supporting frame 2. The flange at its outer end has a bearing 11 on said frame. These bearings may be of any desired construction. The inner section 4 of 10 the nozzle is bell-shaped and said bell-shaped nozzle, between the outer edge 12 of the bell and the inner threaded part 13 thereof, is formed with inwardly projecting 15 teeth or fingers 14. As herein shown, these fingers are struck up from the metal forming this section of the nozzle. It will be obvious that these fingers or teeth may be otherwise formed. It is essential, however, 20 that these fingers or teeth shall not only project inwardly toward the center line of the nozzle, but said teeth or fingers should also project slightly in the direction of the suction, so that the cotton fiber engaged by 25 these fingers or teeth will be held from outward movement relative to the nozzle and may readily move inwardly into the shank of the nozzle and the conveyer pipe through the action of the suction on the cotton fiber. 30 A shaft 15 is journaled in a suitable bearing 16 in the supporting frame 2, and this shaft carries a gear 17, which meshes with a gear 18 attached to the sleeve on the rotating support 6. The shaft 15 is adapted 35 to be connected to a flexible shaft which is rotated by any suitable means.

The outer section 5 of the nozzle is in the shape of an annulus which is concavo-convex in transverse section. This outer section 40 5 is mounted on three rods 19. The rods extend outwardly and backwardly and are clamped to the supporting frame 2. Each rod is formed with two slots 20 and screws 21 passing through the slots hold the 45 rods so that they may be adjusted on the nozzle. The outer section 5 is provided, as herein shown, with four outwardly projecting members or wings 22. These wings are preferably formed integral with the 50 outer member and the outer edges 23 are rounded, as shown in the drawings. The part 24 of each wing extends inwardly slightly over the central opening 25 through the inner section of the nozzle. These wings 55 are also inclined to the outer section and each wing is inclined in the same manner. That is to say, these wings are inclined to a plane at right angles to the axis of rotation of the nozzle section. The edges of the 60 wings are rounded for the purpose of preventing the cotton fiber from being caught and locked thereby. The wings project inwardly over the opening 25, so as to restrict this opening to a certain extent and thus 65 prevent the bolls from being drawn through

the opening. The wings are inclined, as shown in the drawings, for the purpose of moving the boll outward away from the nozzle when this member is rotated relative to the inner section of the nozzle. The inner 70 concave face of the outer section receives the outer edge 12 of the bell of the inner section of the nozzle. The outer section, however, is spaced from the edge 12 of the bell so as to permit air to enter the nozzle between 75 the sections. This space may be adjusted by loosening the screws 21 and shifting the position of the supporting rods 19 relative to the frame 2.

In the operation of the device, as above 80 described, the nozzle is placed under suction in the usual manner and the shaft 15 is rotated. The rotation of the shaft 15 will rotate the inner section of the nozzle on the supporting frame, the outer section 5 being 85 held stationary with the frame. When the nozzle is presented to the cotton boll, the cotton fiber will be drawn by suction through the opening 25 and will be caught by the teeth or fingers 14 on the inner section 90 of the nozzle, and as this section rotates the cotton fiber will be rotated and twisted out of the boll. The wings 22 engaging the boll hold the boll from rotation during this twisting action of the inner section 95 of the nozzle on the cotton fiber. If the boll does rotate on this outer stationary section, the parts will be moved up the inclined wings, which movement of the boll away from the nozzle assists in stripping 100 the cotton fiber from the boll. Furthermore, this outward movement of the parts of the boll away from the inner nozzle, also moves the boll away from the point of maximum suction, so that when the fiber 105 is finally stripped from the boll, the parts of the boll are so located that they will not be drawn into the nozzle. Furthermore, if the rotation of the inner nozzle should cause the boll to spin on the outer section, these 110 wings will serve to throw the parts of the boll away from the nozzle. From the above statement, it will be apparent that the wings on the outer section of the nozzle have several functions depending upon the 115 character and condition of the boll from which the cotton is to be stripped. These wings may serve as abutments which will prevent the boll from rotating and permit the cotton fiber to be stripped therefrom, 120 or they may serve as partial abutments which permit the boll to rotate to a certain extent and be forced outward away from the nozzle by the wings, or, if the boll rotates with the cotton fiber, then these 125 wings will throw the boll outward away from the nozzle.

Part of the air enters the nozzle through the opening 25, while part of the air enters the inner nozzle through the space between 130

the outer section and the inner section and through the openings made in the wall of the inner nozzle when forming the teeth or fingers 14. Therefore, the force of the inrushing air, that is the suction effect, at the extreme outer end of the nozzle or picking region is less than the force of the inrushing air or suction effect in the shank of the inner nozzle, and I am thereby able 5 to proportion the amount of air entering the opening 25 so as to avoid drawing in the twigs and bolls and still maintain sufficient inrushing air or suction to carry the cotton fiber from the inner nozzle to the 10 storage receptacle. This greatly facilitates the clean picking.

In Fig. 4 of the drawings, I have shown a slightly modified form of the invention, as, in this figure, the inner section of the 15 nozzle is held from rotation while the outer section rotates relative thereto. Referring to this figure, my improved picking nozzle consists of a supporting shank 26, to which the flexible suction pipe is attached, and 20 the inner section 4 of the nozzle has a threaded engagement 28 with this shank 26, so that this inner section is held from rotation. Said inner section is bell-shaped and 25 is provided with holding fingers or teeth 14, such as described above. The outer member 5, having the wings 22, is similar in construction to the outer section above described, and this outer section is carried by the rods 19, which are adjustably at- 30 tached by slots and screws 20 and 21 to a rotating part 29. This rotating part has a bearing at 30 on the shank 26 and also a bearing at 31 on a disk 32, carried by the shank 26. Said rotating part 29 has 35 an internal gear 33 which meshes with a gear 34 on the shank 15, which rotates in the bearing 16 formed in the disk 32. As the shaft 15 rotates, the outer part 29 will be rotated relative to the supporting shank 40 26 and the outer section 5 will thereby be rotated relative to the inner section of the picking nozzle. In the operation of this device the outer part rotates. The cotton fiber is engaged by the teeth or fingers 14 45 and the outer part rotating will rotate the boll, the wings 22 serving as abutments to cause the boll to rotate and this will twist the boll so as to strip the cotton fiber therefrom. The rotation of this outer section 55 not only strips the boll from the cotton fiber, but the movement of the wings 22 will throw the parts of the boll outward away from the nozzle.

In Fig. 5 of the drawings, I have shown 60 a still further modified form of the invention, in that both the inner and outer sections of the nozzle are rotated, but are rotated in opposite directions. In this form of the invention, the picker consists of a 65 supporting shank 35, which is connected to

the usual flexible suction pipe, and this shank 35 carries a supporting frame 36, which is threaded thereon. The inner section 4 of the nozzle is threaded on to a sleeve 37. This sleeve is in alinement with the 70 supporting shank 35 and has a bearing connection 38 on the supporting frame 36. The outer section 5 of the nozzle, carrying the wings 22, is supported by the rods 19, which are adjustably attached by slots 20 75 and screws 21 to a rotating outer sleeve 39. This outer sleeve 39 has a bearing connection 40 with the inner sleeve 37. This sleeve 39 also has a bearing connection with the supporting frame 36. These bearings are 80 so arranged that the sleeves 37 and 39 are held rotatably on the shank 35 and frame 36, and one sleeve can rotate in one direction while the other sleeve rotates in the opposite direction. The shaft 15 is mounted 85 in a bearing 16 carried by the frame 36. This shaft has a gear 41, which meshes with a gear 42 on the sleeve 37. Said shaft also has a second gear 43 which meshes with an internal gear 44 on the sleeve 39. As the shaft 15 90 is rotated, the sleeve 37 will be rotated in one direction, while the sleeve 39 is rotated in the opposite direction. The operation of this nozzle will be obvious from the above description. The cotton fiber is engaged by 95 the inner section 4, while the boll comes in contact with the outer section 5. The rotation of these parts in opposite directions will twist the cotton fiber held by the fingers or teeth on the inner section from the 100 boll held by the wings 22 on the outer section.

When the outer section 5 is rotated it is always rotated in the direction of the arrow, indicated in Figs. 2 and 3 and the inner 105 section when rotated is always rotated in the opposite direction, as indicated in Fig. 2 of the drawings.

It is obvious that minor changes in the details of construction and arrangement of 110 parts may be made without departing from the spirit of the invention, as set forth in the appended claims.

Having thus described my invention, what I claim as new and desire to secure by Letters Patent is:

1. A pneumatic cotton picking nozzle including in combination an inner section having means for engaging and holding the cotton fiber from outward movement relative thereto, an outer section having outwardly projecting spaced members fixed thereto for engaging the boll, and means for giving said inner and outer sections a relative rotation, said members being inclined to a plane substantially at right angles to the longitudinal axis of the nozzle and operating to carry the bolls outwardly away from the nozzle.

2. A pneumatic cotton picking nozzle in-

cluding in combination an inner section having means for engaging and holding the cotton fiber from outward movement relative thereto, an outer section having outwardly projecting spaced members fixed thereto for engaging the boll, and means for rotating said inner section relative to said outer section, said members being inclined to a plane substantially at right angles to the longitudinal axis of the nozzle and operating to carry the bolls outwardly away from the nozzle.

3. A pneumatic cotton picking nozzle including in combination an inner section having means for engaging and holding the cotton fiber from outward movement relative thereto, an outer section having outwardly projecting spaced members fixed thereto for engaging the boll, said outer section being spaced from said inner section and substantially in alinement therewith so that air may enter the nozzle between said sections, and means for giving said inner and outer sections a relative rotation, said members being inclined to a plane substantially at right angles to the longitudinal axis of the nozzle and operating to carry the bolls outwardly away from the nozzle.

30 4. A pneumatic cotton picking nozzle including in combination an inner section having a bell-shaped mouth, means formed on the inner surface of said mouth for holding the cotton fiber from outward movement relative thereto, an outer section extending beyond said inner section and having an opening therethrough in line with the opening through the inner section, said outer section having outwardly projecting members on the outer face thereof, said members being inclined to a plane substantially at right angles to the longitudinal axis of the nozzle and operating to carry the bolls outwardly away from the nozzle, and means for giving said inner and outer sections a relative rotation.

5. A pneumatic cotton picking nozzle including in combination an inner section having a bell-shaped mouth, means formed on the inner surface of said mouth for holding the cotton fiber from outward movement relative thereto, an outer section extending beyond said inner section and having an opening therethrough in line with the opening through the inner section, said outer section having outwardly projecting members on the outer face thereof, said members being inclined to a plane substantially at right angles to the longitudinal axis of the nozzle and operating to carry the bolls outwardly away from the nozzle, and means for rotating said inner section relative to said outer section.

6. A pneumatic cotton picking nozzle including in combination an inner section hav-

ing a bell-shaped mouth, means formed on the inner surface of said mouth for holding the cotton fiber from outward movement relative thereto, an outer section extending beyond said inner section and having an opening therethrough in line with the opening through the inner section, said outer section having outwardly projecting members on the outer face thereof, said members being inclined to a plane substantially at right angles to the longitudinal axis of the nozzle and operating to carry the bolls outwardly away from the nozzle, means for holding said outer section from rotation, and means for rotating said inner section.

7. A pneumatic cotton picking nozzle including in combination an inner section having a bell-shaped mouth, means formed on the inner surface of said mouth for holding the cotton fiber from outward movement relative thereto, an outer section extending beyond said inner section and having an opening therethrough in line with the opening through the inner section, said outer section having outwardly projecting members on the outer face thereof, said members being inclined to a plane substantially at right angles to the longitudinal axis of the nozzle and operating to carry the bolls outwardly away from the nozzle, said outer section being spaced from the inner section to permit air to enter the nozzle between said sections, and means for giving said inner and outer sections a relative rotation.

8. A pneumatic cotton picking nozzle including in combination an inner section, an outer section, said inner section having a bell-shaped mouth, said outer section being located beyond the said bell-shaped mouth and having an opening therethrough in line with the opening in said bell-shaped mouth, the outer face of said outer section adjacent said opening therethrough being convex and having outwardly projecting wings formed thereon, and means for giving said inner and outer sections a relative rotation.

9. A pneumatic cotton picking nozzle including in combination an inner section, an outer section, said inner section having a bell-shaped mouth, said outer section being located beyond the said bell-shaped mouth and having an opening therethrough in line with the opening in said bell-shaped mouth, the outer face of said outer section adjacent said opening therethrough being convex and having outwardly projecting wings formed thereon, and means for giving said inner and outer sections a relative rotation, said wings being inclined in the same direction to the outer surface of said outer member.

10. A pneumatic cotton picking nozzle including in combination an inner section, an outer section, said inner section having a bell-shaped mouth, said outer section being

- located beyond the said bell-shaped mouth and having an opening therethrough in line with the opening in said bell-shaped mouth, the outer face of said outer section adjacent 5 said opening therethrough being convex and having outwardly projecting wings formed thereon, and means for giving said inner and outer sections a relative rotation, said wings being each inclined in the same direction to the outer surface of said outer member, the outer edges of said wings being rounded and each wing having an inner part projecting over the opening through said outer section.
- 10 11. A pneumatic cotton picking nozzle including in combination an inner section having a bell shaped mouth with inwardly projecting fingers for holding the cotton fiber from outward movement, an outer section located beyond the said inner section, said outer section having projecting wings formed on its outer face, means for supporting said outer section whereby the same may be adjusted toward and from the inner section, and means for rotating said sections relative to each other.
- 15 12. A pneumatic cotton picking nozzle including in combination an inner section having a bell-shaped mouth with inwardly projecting fingers thereon for engaging and holding the cotton fiber from outward movement, an outer section located beyond said inner section and spaced therefrom, said outer section being in the shape of an annulus which is concavo-convex in cross section, the outer surface thereof being convex, said outer section having wings formed on the outer face thereof, each of which is inclined in the same direction relative to the
- outer section, said wings having their edges 40 rounded and the inner parts thereof projecting over the opening through said outer section, means for adjustably supporting said outer section relative to said inner section whereby the space between the sections may 45 be varied, and means for giving said inner and outer sections a relative rotation.
13. A pneumatic cotton picking nozzle including in combination, an inner and an outer section, said inner and outer sections 50 having a relative rotation, and means carried by the outer section and extending outwardly therefrom for engaging the bolls and twigs, said means being inclined relative to the plane of rotation of said sections, for 55 moving the same outward away from the nozzle, thereby reducing the suction effect thereon and lessening the chance of drawing the bolls and twigs into the nozzle.
14. A pneumatic cotton picking nozzle including in combination, an inner section and an outer section, said sections having a relative rotation, said inner section having means for engaging the cotton fiber, and said outer section having means extending outwardly therefrom for engaging the bolls, said means being inclined relative to the plane of rotation of said sections, for moving the same outward away from the nozzle, thereby reducing the suction effect thereon 70 and lessening the chance of drawing said bolls and twigs into the nozzle.

In testimony whereof I herewith affix my signature, in the presence of two witnesses.

THEODORE E. STRAUS.
